FILING DEVICE

Louis Rostoker, Toronto, Ontario, and Alfred E. Finn, Leaside, Ontario, Canada

Application October 28, 1947, Serial No. 732,580

4 Claims. (Cl. 129—11)

1

This invention relates to a filing device, such as is commonly used to file bills, invoices and other papers.

Such devices commonly comprise two pointed posts on which the paper is impaled, and two curved arms adapted to be swung or rocked to register with the posts and retain the papers thereon.

The objects of this invention are two fold. First to provide simple and effectual means to yieldingly retain the arms in post registering and/or post non-registering position, and secondly to provide means for locking the posts in registering or paper retaining position and/or non-registering position.

The objects of this invention are achieved by the means hereinafter described and illustrated, by way of example, in the accompanying drawings in which

Fig. 1 is a top plan view;

Fig. 2 is a cross-section on the line 2—2 in Fig. 3;

Fig. 3 is a view of the underside partly broken away; and

Fig. 4 is a fragmentary perspective view of the rod connecting the arms.

In the drawings like numerals of reference indicate corresponding parts in the different figures.

Base 1 is a flat piece of metal with a raised portion 1^a with a hollow interior which contains the mechanism for controlling the curved arms. Base plate 2 covers the hollow interior of the raised portion 1^a.

The vertical posts 3 are rigidly secured to the base 1 and are hollow and provided with a bevelled end to receive curved arms 4, 4. Arms 4, 4 are adapted to swing or rock back and forth from post engaging position shown in full lines in Fig. 2 to post non-engaging position shown in dotted lines in Fig. 2.

Arms 4, 4 extend through transverse slots 5, 5 in the wall of the raised portion 1^a of the base 1 into the hollow interior. In closed position the arms 4 extend upwardly adjacent the front ends of the slots 5, 5. In open position they swing back to the rear ends of the slots.

The arms 4, 4 are joined by rod 4^b which may be integral with the arms and which extends lengthwise of the hollow interior of the raised portion of 1^a of the base 1. The rod 4^b is rockable between lugs 6, 6 and lug 7 (see Fig. 3) which bear or engage against opposite sides of the rod 4^b thus serving with the top wall of the base 55 the arms to swing back. When slid in the other

2

portion 1^a and the base plate 2 as journals or bearings for said rod 4^b.

The rod 4^b, which is round, is provided with two flat surfaces, technically called "flats," 8 and 9, extending at an angle of about 40° to one another, against which bear springs 10 and 11 respectively. Base plate 2 is applied over the hollow interior of the raised portion 1^a of the base and is secured by a screw 12 screwed into internally threaded boss 13, and is provided with lugs 14, 14 which project into the interior and engage the ends of spring 10 when the base plate is screwed down. Corresponding lugs, which are not shown, due to the fact that base plate 2 is cut away to show the interior in Fig. 3, bear on the ends of spring 11.

Engagement of the lugs on the ends of the springs cause the springs 10 and 11 to slightly bend across the round rod 4^b at the points where the rods are provided with the flats 8 and 9. Flat 8 is horizontal when the arms are in closed or post registering position and spring 10 bearing on this flat surface yieldingly retains them in that position. Flat 9 is horizontal when the arms are in open or post non-registering position and spring 11 bearing on this flat surface yieldingly retains them in open position. When the springs are bearing on the flats they are substantially straight, not distorted, thus insuring a minimum of strain on the springs and hence longer life. Since it is desired to insure that the arms will be swung back into closed position the spring 10 is made of heavier, stronger, resilient material than spring 11 to insure that the arms will swing fully into closed position.

Of course the arms may be readily swung from open to closed position and vice versa by the user's hand except when locked in closed position by the hereinafter described means.

A flat locking bar 16 is slidably mounted on portion 1^a of base 1 by means of headed screws or pins 17, 17 which project from portion 1^a through longitudinal slots 16^a, 16^a in bar 16. The bar is located so that it passes over the rear ends of slots 5, 5 and is provided with an upturned flange 16^d on its inner longitudinal edge adapted to engage the rear of arms 4, 4 to prevent them from rocking out of post engaging position. Two slots 16^b, 16^b are provided in the bar 16 to receive the arms 4, 4 when swung back into open or non-post registering position. When the locking bar is slid to the left in Fig. 1 to the position shown in dotted lines these slots register with slots 5, 5 in the base and permit the arms to swing back. When slid in the other

direction, to the right in Fig. 1 the flange is in substantially engaging position with the arms to lock them in closed position.

To normally urge the locking bar to locking position the bar 16 is provided with a down turned lug 16^c at one end thereof. Studs 18^a and 15^b and base portion 1^a respectively receive spring 19 which bears against lug 16^c and base portion 1^a. It is held under tension and constantly urges the locking bar into locking position.

When the arms 4, 4 are in slots 16^b, 16^b they act as stops preventing the spring from moving the locking bar. When the operator swings the arms 4, 4 to closed position the spring 19 automatically slides the bar to locking position. To open the arms it is only necessary for the operator to press on lug 16^c to move the locking bar to the left in Fig. 1, to position shown in dotted lines in which the slots 16^b, 16^b register with slots 5, 5, and then push the arms back to non-post registering position.

It will be seen from the above description that the device described achieves the objects of this invention. Although described in some detail by way of illustration, it is obvious that various modifications of the invention are possible without departing from the spirit thereof.

What we claim as our invention is:

1. A filing device comprising in combination a base having a hollow portion open at the underside and a pair of slots through its upper side, a pair of posts projecting upwardly from the base and rigidly secured thereto, a pair of retaining arms pivotally mounted on the base and rockable into and out of registering position with the posts, the lower ends of said arms extending through the slots in the hollow portion of the base, a rod connecting the lower ends of the retaining arms and extending through the hollow base portion and provided with a flat thereon, a leaf spring extending transversely of the rod opposite the flat, a plate for closing the underside of the hollow base, said plate being provided with lugs engaging opposite ends of the leaf spring to cause it to bear against the rod and engage the flat to yieldingly hold the arms in a predetermined position, and screw means for detachably securing said plate to the base.

2. A filing device comprising in combination a base having a hollow portion open at the underside and a pair of slots through its upper side, a pair of posts projecting upwardly from the base and rigidly secured thereto, a pair of retaining arms pivotally mounted on the base and rockable into and out of registering position with the posts, the lower ends of said arms extending through the slots in the hollow portion of the base, a rod connecting the lower ends of the retaining arms

and extending through the hollow base portion and provided with two longitudinally spaced flats thereon arranged at different angles, a pair of leaf springs extending transversely of the rod one opposite each flat, a plate for closing the underside of the hollow base, said plate being provided with lugs engaging opposite ends of the leaf spring to cause them to bear against the rod and engage the flats to yieldingly hold the arms in and out of post registering position, and screw means for detachably securing said plate to the base.

3. A filing device as claimed in claim 2 in which the leaf spring which holds the arms in post engaging position is heavier than the spring which holds it out of post engaging position.

4. A filing device comprising in combination a base having a hollow portion open at the underside and a pair of slots through its upper side, a pair of posts projecting upwardly from the base and rigidly secured thereto, a pair of retaining arms pivotally mounted on the base and rockable into and out of registering position with the posts, the lower ends of said arms extending through the slots in the hollow portion of the base, a rod connecting the lower ends of the retaining arms and extending through the hollow base portion and provided with a flat thereon, a leaf spring extending transversely of the rod opposite the flat, a plate for closing the underside of the hollow base, said plate being provided with lugs engaging opposite ends of the leaf spring to cause it to bear against the rod and engage the flat to yieldingly hold the arms in a predetermined position, screw means for detachably securing said plate to the base, and means mounted on the base for locking the arms in post registering position comprising a bar, one side of which is provided with an upturned flange and engages the arms to retain them in post registering position and provided with slots therein to receive the arms in post non-registering position, said bar being slideable into and out of locking position, and spring means urging the bar into locking position.
